UNITED STATES PATENT OFFICE.

WILLIAM GODDU, OF WINCHESTER, MASSACHUSETTS.

NAILING-MACHINE.

SPECIFICATION forming part of Letters Patent No. 595,878, dated December 21, 1897.

Application filed August 5, 1897. Serial No. 647,168. (No model.)

To all whom it may concern:

Be it known that I, WILLIAM GODDU, residing in Winchester, in the county of Middlesex and State of Massachusetts, have invented an Improvement in Nailing-Machines, of which the following description, in connection with the accompanying drawings, is a specification, like letters and figures on the drawings representing like parts.

This invention relates to a nailing-machine and is herein shown as embodied in a machine adapted to be operated by hand and technically known as a "hand-tacker."

In accordance with this invention the machine is provided with a holder or receptacle for the tacks or nails, which is movable with the driver-bar, so as to agitate the nails or tacks and thus supply the same to the roadway, from which the tacks or nails are delivered one by one to a nail-delivering passage preferably made in what may be termed the "body" or "stationary" portion of the machine and which communicates with a passage for the driver. The nail-delivering passage communicates at its lower end with the driver-passage for the delivery of the nails or tacks into the said driver-passage, and at its upper end it is adapted to communicate with the slot or passage in the roadway when the latter is in what may be termed its "lowered" position, in which position the endmost nail in the roadway is transferred to the nail-delivering passage by a separator, as will be described. These and other features of this invention will be pointed out in the claims at the end of this specification.

Figure 1 is a side elevation, with parts broken away, of a nailing-machine embodying this invention; Fig. 2, a front elevation 40 of the machine shown in Fig. 1; Fig. 3, a vertical longitudinal section of the machine shown in Fig. 1, with the driver-bar elevated; and Fig. 4, a front elevation of the machine with the parts in the position they occupy 45 when the driver-bar is elevated, as shown in Fig. 4.

In the present instance I have illustrated my invention as embodied in a hand tool or machine comprising a body portion A, which 50 is adapted to be grasped by the hand of the operator and held stationary against the work—such, for instance, as the upper of a

boot or shoe—and a movable head or upper portion A', which may be provided, as shown, with a handle a. The body portion A is preferably made in two parts a' a'', secured together, as by screws a'', and having formed in them a slot a⁴ for the reception of a driver-bar a⁵, a passage a⁶ for the reception of a driver a⁷, secured to the driver-bar, as by a screw a⁸, and preferably a nail or tack delivering slot or passage a⁹, which communicates at its lower end with the driver-passage a⁶ and at its upper end terminates flush with the inner face of an extension or upright a¹⁰ 65 of the said body.

The driver-bar a⁵ is secured to or forms part of the movable upper portion or head A', having secured to or forming part of it above the driver a⁷ a nail receptacle or holder b, 70 which, as herein shown, comprises an upwardly-inclined bottom b', a rearwardly inclined or curved top b², and sides b³ b⁴, the side b³ being preferably made movable, so as to uncover the said receptacle or holder, and 75 in the present instance the said side is represented as pivoted at b⁵ and provided with hook or latch b⁶, which is adapted to engage a pin b⁷ to secure the cover or movable side b³ in its closed position.

The movable head A' is cored or otherwise formed to receive a roadway b¹⁰ for the nails, which is extended into the holder or receptacle b and is provided with a suitable slot or nail-passage b¹², down which the nails or tacks 85 b¹³ descend. The slot b¹² in the roadway may be enlarged at its rear end, as at 3, for the ready reception of the tacks or nails, which are retained in said slot by the head A and a retaining strip, piece, or guard b¹⁵. The roadway at its lower or delivery end is formed so as to leave a passage for a knife or blade c, attached to a lever c' and constituting a separator or transerrer by which the endmost nail in the roadway is transferred into the 95 passage a⁹ when the driver a⁷ is in its lowered position. The lever c', as shown, is pivoted to the head A' at c² and is moved in one direction by a spring c³, having one end secured to the head and its other end to the separator-lever c', the said spring acting to keep the lever c' in engagement with a cam-surface c⁴ on the side of the upright or extension a¹⁰, so that the said lever may follow the path or

shape of the cam and move so as to cover and uncover the slot in the roadway at the proper time.

In Fig. 1 the parts are in the position they occupy when a nail or tack has been driven, the movable head and its attached driver-bar and driver having been moved by the operator down toward the body portion A, which may be supposed to have its nose d pressed against the work. A nail or tack having been driven into the work, the head A' is lifted by the operator into substantially the position represented in Figs. 3 and 4. On the upward movement or stroke of the head and its attached parts the driver a⁷ is lifted, so as to uncover the discharge end of the nail-delivering slot or passage a⁹, which permits a nail therein to drop into the driver-passage a⁶ in the nose. As the head is moved up the separator knife or blade c is moved outward by the cam c⁴, so as to uncover the slot in the roadway, and when the said separator has been moved sufficiently to wholly uncover the slot in the roadway the latter will be at such time covered by the extension a¹⁰, as represented in Fig. 3.

The tool or machine is now in condition to drive the nail in the driver-passage, which is effected by the operator moving the head A' toward the body A and from the position shown in Figs. 3 and 4 to that shown in Figs. 1 and 2. On the downstroke of the head and driver the separator-blade is moved inward by its spring c⁸ keeping its lever c' in engagement with the cam c⁴, and the said separator-blade passes behind the endmost nail in the roadway, and when the slot in the roadway is brought in line with the inlet mouth or end of the nail-passage a⁹ the separator-blade will at such time transfer the endmost nail into said passage and at the same time close the slot in the roadway.

The nail or tack delivered into the passage a⁹ on the downstroke of the driver will descend into the driver-passage a⁶ on the next upstroke of the said driver. The nails or tacks in the receptacle are agitated by the movement of the said receptacle with the driver and drop into the slot in the roadway, and on the downstroke of the driver the nails or tacks in the receptacle will fly up and strike the rearwardly curved or inclined front upper portion 2 of the receptacle and be directed down over the enlargement 3 in the roadway, so that the latter may be kept full of nails.

In practice the body portion A of the tool is moved over the work between the down-strokes of the driver, and ordinarily the driver a⁷ will close the mouth of the passage a⁹ while the position of the tool with relation to the work is being changed; but to prevent the tack or nail in the passage a⁹ dropping into the driver-passage a⁶ and then out therefrom by the operator moving the driver into its upper position (shown in Fig. 3) while the tool is lifted off from the work in the act

of bringing its nose into a new position—that is, into engagement with another portion of the work—I have provided means for closing the said driver-passage, which is automatically removed by the nail or tack when the latter is driven. The means referred to may be a substantially light strip of spring metal f, (see Fig. 3,) which is secured in a slot f' in the body portion at one end by a screw f² and has its free or lower end normally extended across or into the driver-passage a⁶, as represented in Fig. 3, a sufficient distance to practically close the said passage at its bottom, but which spring yields to the tack or nail as the latter is forced out of the passage a⁶ by the driver.

I claim—

1. In a nailing-machine, the combination with a body portion provided with a driver-passage and with a nail-delivering passage communicating with said driver-passage, of a movable head carrying a nail-receptacle, a roadway, a separator, and a driver, and a cam on said body portion to operate said separator, substantially as described.

2. In a nailing-machine, the combination with a movable driver, of a receptacle for loose nails movable therewith, and provided with a roadway having a slot for the passage of the said loose nails out of said receptacle, and a separator coöperating with said roadway, substantially as described.

3. In a nailing-machine, the combination with a body portion provided with a driver-passage and with a nail-delivering passage communicating with said driver-passage, of a movable head carrying a nail-receptacle provided with a roadway having a slot for the passage of the nails adapted to communicate with the nail-delivering passage in the said body portion, means to transfer the nails from the roadway into said delivering-slot, and a driver movable with said head, substantially as described.

4. In a nailing-machine, the combination with a driver, of a nail-receptacle movable therewith to agitate the nails therein, and a roadway extended into said receptacle to receive the agitated nails, substantially as described.

5. In a nailing-machine, the combination with a driver, a nail-receptacle movable therewith to agitate the nails therein, a roadway extended into said receptacle to receive the agitated nails, and a separator movable with the driver and coöperating with said roadway, of a body portion provided with a passage into which said nails are transferred by said separator, and a cam attached to said body portion to operate said separator, substantially as described.

6. In a nailing-machine, the combination with a body portion provided with a driver-passage and with a nail-delivering passage communicating with said driver-passage, of a head movable toward and from said body portion and provided with a driver-bar, a driver attached thereto, a roadway carried by said

- head and adapted to communicate with the nail-delivering passage in said body portion, a separator carried by said head and coöperating with said roadway, and a cam attached to the body portion to operate said separator, substantially as described.
5. In a nailing-machine, the combination with a movable driver, of a roadway movable therewith, a separator coöperating with said roadway, a body portion in which said driver is movable a cam attached to said body portion to operate said separator to close the said roadway when the driver is moved in one direction and means independent of the separator, to close said roadway when the driver is moved in the opposite direction, substantially as described.
7. In a nailing-machine, the combination with a movable driver, of a roadway movable therewith, a separator coöperating with said roadway, a body portion in which said driver is movable a cam attached to said body portion to operate said separator to close the said roadway when the driver is moved in one direction and means independent of the separator, to close said roadway when the driver is moved in the opposite direction, substantially as described.
8. In a nailing-machine, the combination with a body portion provided with a nose having a passage for the reception of the nails to be driven, of a driver movable in said passage, a driver-bar, a roadway movable with said driver-bar and having a slot for the passage of the said nails, a separator coöperating with said roadway, means to operate said separator to remove a nail from the slotted roadway, and a passage to convey the separated nail into the passage in the nose, substantially as described.
10. In a nailing-machine, the combination of the following instrumentalities, viz: a reciprocating driver, a slotted roadway movable therewith and located above said driver, a separator coöperating with said roadway, a nose having a passage for the said driver, means to connect the slot in the roadway above the driver with the driver-passage in said nose, and means to operate said separator, substantially as described.
11. In a nailing-machine, the combination of the following instrumentalities, viz: a reciprocating driver, a roadway movable therewith and located above said driver, a separator coöperating with said roadway, a nose having a passage for the said driver, means to connect the roadway above the driver with the driver-passage in said nose, means to operate said separator, and means to close the driver-passage, substantially as described.
10. In a nailing-machine, the combination of the following instrumentalities, viz: a reciprocating driver, a roadway movable therewith and located above said driver, a separator coöperating with said roadway, a nose having a passage for the said driver, means to connect the roadway above the driver with the driver-passage in said nose, means to operate said separator, and means to close the driver-passage, substantially as described.
11. In a nailing-machine, the combination of the following instrumentalities, viz: a reciprocating driver-bar provided with a driver movable in the passage in the said nose, a nail-receptacle movable with the driver-bar, a nail-delivering passage to connect the nail-receptacle with the driver-passage in the nose, and means to transfer the nails from the said receptacle to said nail-delivering passage, substantially as described.
- In testimony whereof I have signed my name to this specification in the presence of two subscribing witnesses.
